(57) **CLAIM**

The ornamental design for a patient interface, as shown and described.

DESCRIPTION

FIG. 1 is a front perspective view of a patient interface showing a first embodiment according to our new design; FIG. 2 is a front view thereof; FIG. 3 is a rear view thereof; FIG. 4 is a top view thereof; FIG. 5 is a bottom view thereof; FIG. 6 is a left side view thereof; FIG. 7 is a right side view thereof; FIG. 8 is a front perspective view of a patient interface showing a second embodiment according to our new design; FIG. 9 is a front view thereof; FIG. 10 is a rear view thereof; FIG. 11 is a top view thereof; FIG. 12 is a bottom view thereof; FIG. 13 is a left side view thereof; and, FIG. 14 is a right side view thereof.

The broken lines in the drawing illustrate portions of the patient interface that do not form part of the claimed design. Line shading and stippling have been used in the drawings to indicate a contrast in appearance.

1 Claim, 14 Drawing Sheets
